UNITED STATES PATENT OFFICE.

EDWIN F. TAYLOR, OF WYNCOTE, PENNSYLVANIA.

ELASTIC-FLUID TURBINE.

No. 825,164.

Specification of Letters Patent.

Patented July 3, 1906.

Application filed October 29, 1904. Serial No. 230,536.

To all whom it may concern:

Be it known that I, EDWIN F. TAYLOR, a citizen of the United States, residing at Wyncote, in the county of Montgomery and State of Pennsylvania, have invented certain new and useful Improvements in Elastic-Fluid Turbines; and I do hereby declare the following to be a full, clear, and exact description of the invention, such as will enable others skilled in the art to which it appertains to make and use the same.

This invention, which relates to elastic-fluid turbines, contemplates certain new and useful improvements designed more especially for employment in connection with the constructions of turbines for which Letters Patent numbered 752,602, 752,603, and 752,604 were issued to me on or about the 16th day of February, 1904. It is to be understood, however, that the present improvements are equally capable of utilization in connection with other existing turbine constructions and no limitation is intended by the reference to my patents above noted. Neither do I limit the application of the improvements to any particular class of turbine, although I have illustrated and describe hereinafter a multiple-wheel engine of the impact-reaction type embodying the present novel and useful features of construction.

Referring to my patented constructions above noted, it is patent that the motive fluid therein is expanded through a series of nozzle-sections and creates impact and reactive forces on blades or buckets carried by moving parts located alternately between the successive nozzle-sections, which nozzle-sections are so proportioned that an adiabatic partial expansion of the fluid may be effected in each section of the complete nozzle. The kinetic force of the fluid due to such expansion is accelerated at the point of impact through a change in entropy of the fluid immediately following its release from the nozzle-section and yields up its heat on the moving part in proportion to the degree of expansion created in the nozzle-section. The fluid having thus performed work through the medium of the power-transmitting shaft by giving up its heat through impact in proportion to the degree of its expansion, assumes a temperature corresponding to the remaining pressure maintained and is again in a normal

condition. From this state the fluid is again adiabatically partially expanded through a succeeding nozzle-section, the degree of this expansion corresponding to that of the previous expansion, and substantially the same degree of heat, together with substantially the same amount of energy, is therefore applied in the second stage, and so on throughout the range, all of the nozzle-sections being constructed and arranged to deliver an equal amount of energy on each moving part of the series and to effect a continuous adiabatic expansion of the motive fluid. The degree of expansion of the fluid effected in the nozzle-sections is determined by the velocity of and the degree of heat from the fluid required for the impact on the moving part, the nozzle-sections being proportioned to obtain the desired result. For example, in a high-speed turbine a lesser number of nozzle-sections are required, but said sections are necessarily proportioned to create an adiabatic partial expansion of the fluid to a lower pressure and to effect a complete expansion of the fluid with a less number of stages than is demanded in a slower-velocity turbine. It will of course be understood that a speed corresponding to the highest theoretical efficiency is to be desired. Nevertheless turbines can be constructed along the stated lines to have wide ranges of velocities with but slightly impaired efficiency.

One of the most difficult problems presented in turbine work is to not only maintain the efficiency throughout the range of load, but to construct a variable-speed turbine and maintain in its operation at various speeds substantially the same degree of efficiency.

The present invention contemplates, among other valuable features hereinafter referred to and described, elements alternately active to create and to direct different degrees of energy against the moving part of the turbine. Said elements may each consist of a nozzle or group of nozzles capable of creating a degree of fluid expansion differing from that created in the nozzle or group of nozzles constituting the other element, the differential elements commonly communicating with a fluid-supply and being alternately active to deliver varying kinetic forces against the impact-surfaces of the movable part, whereby said part is caused to rotate at a greater

- or less speed, dependent upon the requirements. It will be understood from the foregoing that the passage of the fluid is cut off from the one group of nozzles—for example, 5 the high-expansion group—while issuing from the other—the lower expansion group—and vice versa, and the means for accomplishing this alternate action constitutes another feature of the present improvements.
- 10 The manner of controlling the energy of the fluid by changing the degree of expansion through differential nozzle-sections is especially desirable and essential where different velocities are demanded and where substantially the same efficiency must be maintained. The outlined feature is an essential 15 in marine work, since the physical and climatic conditions demand a variable-speed turbine with the greatest degree of economy.
- 20 It is to be understood that this feature, as well as other features of my present invention, is applicable to turbines generally, although for the purpose of illustration I show and describe the improvements embodied in a turbine equipped especially for 25 marine service and adapted for low and high speeds.

The precise nature of the present improvements will now be disclosed, but only in their 30 preferred forms of embodiment, the scope of the concluding claims permitting the various parts and combination of parts to be variously modified and departed from without exceeding the intent of the invention.

35 In connection with the detailed description reference is to be had to the accompanying drawings, in which—

Figure 1 is a side elevation of an elastic-fluid turbine embodying my invention. Fig. 40 2 is a vertical central longitudinal sectional view of the same intermediately broken away. Fig. 3 is a cross-sectional view on line 3 3 of Fig. 2. Fig. 4 is an enlarged sectional view on line 4 of Fig. 3. Fig. 5 is an 45 enlarged view showing the construction and manner of assemblage of the insertible blades or buckets for a reversible moving part or wheel. Fig. 6 is a further enlarged similar view of the blades or buckets for a 50 non-reversible moving part or wheel. Fig. 7 is a detail view of one of the blades or buckets for a reversible moving part or wheel. Fig. 8 is an enlarged sectional view of one of the nozzle-sections and movable and stationary 55 blades or buckets. Fig. 9 is an enlarged detail view of a wheel by which the control of the nozzle-sections is effected. Fig. 10 is an enlarged sectional view of lower and higher speed nozzle-sections, valves therefor, and 60 movable and stationary blades or buckets.

Referring to the drawings by numerals, 1 designates the turbine-casing, in which are a series of moving parts or wheels 2 2, fixed on a shaft 3, common to the entire series.

The shaft is mounted at one end in a journal-box 4, secured to and supported by a radially-ribbed casing-head 5, and is mounted toward its other end in a journal-box 6, supported from the base 7. The shaft-opening in the opposite casing-head 8 is suitably packed, as shown. The shaft terminates at its first-named end preferably within the journal-box 4 and is provided with a collar 9, forming an oil-guard to prevent the entrance of the lubricant into the interior of the casing. The journal-box 4 is covered by a cap 10, screwed between the threaded inner ends of the ribs and serving to exclude air from the casing-interior, as will presently be more 80 fully explained.

The fluid-inlet 11 is shown in Fig. 1 and indicated by dotted lines in Fig. 2. This inlet communicates with a heating-jacket 12, surrounding the casing, and after traversing said jacket the fluid enters a fluid-chest 13 85 through openings provided in the chest-wall 14. The heating-jacket extends between said wall and a partition 15, located at the point in the turbine where the fluid loses the major portion of its heat units and is more 90 or less dependent upon the action of the condenser for its kinetic effect upon the moving parts in the condenser end. The heating-jacket serves, therefore, to obtain the temperatures of the fluid at the several stages 95 while the fluid is kinetically most active, whereas when the fluid is deprived of the major portion of its kinetic energy and is dependent upon the condenser for further action, it is desirable from a standpoint of 100 efficiency and economy to bring the fluid to as low a temperature as possible short of condensation and within a minimum of time. This result is accomplished by confining the heating means to the stages not influenced 105 by the condenser which is connected with the fluid-outlet 16. The jacket is therefore not subjected to such a low degree of temperature as will cause condensation therein. Neither are the stages influenced by the condenser subjected to the action of a heating medium. To obtain the best results from the employment of the heating-jacket, the fluid between the inlet and chest is compelled to traverse a spiral path around the 110 casing, spirally-disposed partitions 17 being interposed between the walls of the casing and jacket, as shown in Fig. 2.

The moving parts, of which there may be any number, depending upon the requirements, each consists of a disk 18, having balancing ball-weight races or grooves at its sides, and said disks are spaced apart by hubbed wheels 19, having rims 20 and keyed or otherwise fixed to the shaft to rotate with the disks. Toward the periphery of each disk are two oppositely-facing concentric series of 115 blades or buckets alternately active to effect 120 125

the rotation of the disk in opposite directions. The blades or buckets may be formed in the disk; but I prefer to construct them separately and interchangeable and fasten them on the disk-⁵rim, as shown more clearly in Fig. 5. Each of the blades or buckets is provided with an inner impact-surface 21 and an outer impact-surface 22, facing a direction opposite to that of the surface 21 and separated therefrom by a segmental portion 23. The blade or bucket terminates at its outer end in a segmental portion 24 and is provided near its inner end with a segmental portion 25, which rests against the periphery of the disk. The outer segmental portion 24 is provided at its opposite edges, respectively, with a groove 26 and a tongue 27, and the intermediate segmental portion 23 is similarly equipped at its edges with a groove 28 and a tongue 29. In assembled condition the blades or buckets are by the provision of the tongues and grooves radially interlocked, thereby effectually resisting the strain due to centrifugal action in rotation. The blades or buckets are fastened to the disk-²⁵rim by shouldered arms or shanks 30, drive-fitted into correspondingly-formed slots 31 in the disk. The shoulders 32 are located at each side of and short of the inner end of an arm 30, with the result that when under strain displacement by the shoulders of the metal around the base of a slot is avoided and the shoulders alone are subjected to strain, which tends to shear them, but which is effectually resisted. To prevent fracture of the disks between the slots therein, the arms and the slots into which they are fitted are alternately of different lengths and the shouldered ends are therefore in staggered relation, as shown.

Fig. 6 illustrates on a larger scale blades or buckets 33, provided with single impact-surfaces and adapted therefore for turbines of the non-reversible type. The peculiar construction of the blades or buckets by which they are caused to interlock with each other and with the disk enables them to effectually resist the strain due to the centrifugal force created by the revolving part. Inasmuch as the blades or buckets and the disk are drive-fitted together, the structure is rendered practically homogeneous with no tendency to separation by reason of the provision for locking the blades or buckets at a plurality of points. The blades or buckets being fashioned each separately may be separately tested for strength, thereby insuring against fracture or distortion and displacement in operation.

The disks 18 extend at their rim portions beyond the rims of the spacing-wheels 19 and between the walls of stationary chambers 34. The first disk of the range extends between the left-hand wall 35 of the first chamber 34

and the wall 14 of the fluid-chest 13. In the fluid-chest wall 14 and in the right-hand wall 36 of each stationary chamber are an inner set of adiabatic expansion-nozzle sections 37 and an outer set of similar nozzle-sections 38, one set being employed to effect the rotation of the moving part in one direction and the other set serving to rotate said part in the reverse direction, as will presently more fully appear. In the wall 35 of each of the stationary chambers are inner and outer concentric series of reaction blades or buckets 39, and by reference to Fig. 8 it will be seen that the construction of the movable and stationary blades or buckets is peculiar, being designed with reference to each other and to the nozzle-sections to obtain the maximum efficiency in action. The blades or buckets are of concavo-convex form, and, referring to the movable impact-blades 21, it will be noted that the arc which forms the concave impact-surface of one blade is drawn from a center, which is also the center of the arc forming the convex surface of the next adjacent blade. The fluid-passage between any two blades is therefore of uniform cross-sectional area throughout, and in said passages no fluid expansions may take place, the expansions occurring in the nozzle-sections alone. The stationary reaction-blades 39 are formed similarly to the impact-blades, but face in a direction opposite to that of the latter. Obviously the blades 39 may be formed separately from and fastened to the chamber-wall. The cross-sectional area of the passage between two reaction-blades is preferably substantially equal to that between the impact-blades, with the purpose of avoiding fluid expansion and scattering and dissipation of the fluid. The convex surfaces are formed of arcs and tangents, the tangential angles of the impact and reaction blade surfaces coinciding in order to maintain an equal cross-sectional area throughout the passages between the impact and reaction blades. This angle of the tangential line of an impact-blade convex surface also coincides with the angle of the shorter wall of a nozzle-section 37, whereby a portion of the passage between the blades 21 forms a continuation of, and consequently lengthens, said nozzle-section, the line of divergence of said section being thereby maintained. A further and very important advantage due to the stated manner of extending the nozzle-section is that the fluid impacts against the moving surfaces at the most desirable point—namely, near the change in direction of the passage. By this arrangement also the energies exerted at the sides of the moving disk are practically equal and the rotating disk is practically balanced between the impact and reactive forces.

The fluid passes from the steam-chest 13

through the outer or inner sets of nozzle-sections, dependent upon the desired direction of rotation of the moving parts, and said nozzle-sections deliver adiabatically partially-expanded fluid against the impact blades or buckets of the first disk. The fluid then moves against the blades or buckets in the wall of the stationary chamber, creating a reaction effect on the disk, after which it enters the chamber, wherein it is in a normal condition. The fluid passes from the chamber through the nozzle-sections in the wall thereof and impacts against the blades or buckets of the second disk, thence enters between the reaction-blades, and so on throughout the range of moving parts. The parts are proportioned to allow of the larger number of the disks receiving the major portion of the kinetic energy of the fluid, and these disks are inclosed, as hereinbefore stated, by the heating-jacket 12. The remaining disks are within the influence of the condenser. Consequently the condenser action on the fluid supplants its otherwise exhausted kinetic energy, and a heating-jacket at these disks is therefore undesirable. The cap 10 effectually excludes air from the condenser end of the turbine, thereby insuring maximum efficiency of the condenser.

The stationary chambers are each divided by a continuous ring partition 40, mounted to be rotated on rollers 41, which travel on the bottom of the chamber. The number and positions of the rollers will depend upon the requirements. The partition provides an inner annular chamber for the fluid entering from the inner nozzle-sections and blades or buckets and an outer annular chamber for the fluid entering from the outer nozzle-sections and blades or buckets, the chambers being separated and non-communicating in every position of the partition. The partition carries outer flange-sections 42 and inner flange-sections 43, and these sections in turn carry valves respectively numbered 44 and 45. By reference more particularly to Fig. 3 it will be seen that there are provided four groups of outer nozzle-sections and three groups of inner nozzle-sections, the outer nozzle-sections being employed to effect the rotation of the moving parts in one direction and the inner nozzle-sections serving to rotate the parts in the reverse direction. The valves are yieldingly supported from the flange-sections through the medium of bolts 46 and interposed coiled springs 47. (See Fig. 4.) In the position of the valves shown in Fig. 3 the first group of outer diametrically opposite nozzles *a a* is uncovered and by partially rotating the ring 40 the second group of nozzles *b b* is uncovered, the first group remaining open. Further rotation of the ring moves the valves to uncover the third group *c c*, and in this position all of the groups are open. The nozzle-sections of the three groups are proportioned to obtain a predetermined velocity, which is gradually reached by the successive uncovering of the groups. Obviously the number of groups and the number of nozzle-sections comprising a group may be varied according to requirements. To obtain a relatively higher rotative speed of the turbine, there are provided nozzle-sections *d d*, which are uncovered by the further movement in the same direction of the ring and valves. In said further movement the uncovered groups of nozzle-sections *a*, *b*, and *c* are closed by the ends 48 of the adjacent valves and the openings between the valves are brought into position to open the higher-speed nozzle-sections, as will be understood. In this manner the maximum velocity is gradually reached, and by reversely rotating the ring and valves the velocity is gradually reduced and the turbine is not subjected to the strain which would be exerted from an abruptly increased or decreased fluid-pressure. It will be noted that the low-speed nozzle-section groups and the high-speed nozzle-sections are alternately in action. This is desirable for the reason given—namely, that a sudden change from a low to a high velocity is objectionable both from the standpoints of efficiency and durability.

As shown and as above explained, the angle of the tangential line of an impact-blade convex surface coincides with the angle of the shorter wall of a nozzle-section, whereby a portion of the passage between two blades forms a continuation of and lengthens said nozzle-section. The higher degree of energy created in the higher-speed nozzle-sections *d* is the result of an increase in divergence of the nozzle-walls, which increases the fluid expansion therein and also the result of lengthening the entire nozzle and changing the angle of inclination to bring the angle of its shorter wall to coincide with the angle of the tangential lines forming part of the convex surfaces of the impact-blades. In further explanation of the action of the higher-speed nozzles it will be assumed, for example, that the fluid has an initial pressure of one hundred and twenty pounds absolute and that the groups of nozzles *a*, *b*, and *c* in the first stage expand the pressure to one hundred pounds, thereby creating a velocity of nine hundred feet per second, which is twice the peripheral velocity of the moving part or four hundred and fifty feet per second. It will be further assumed, for example, that the higher velocity desired for the moving part is five hundred and seventy-five feet per second, resulting from a fluid velocity of eleven hundred and fifty per second, and to obtain this result the higher-speed nozzles, which communicate with the chest supplying the other nozzles, are constructed and arranged to ex-

5 p and the fluid from one hundred and twenty pounds to, say, eighty pounds. The increased expansion for the higher speed has the effect of reducing the number of stages 5 acted upon by the kinetic energy; or, in other words, the zero-point of kinetic energy is changed. The stages not acted upon kinetically are subjected to windage action of the fluid, due to the influence of the condenser, 10 and no loss in efficiency results.

Assuming that the movements of the ring and valves to uncover the low and high speed nozzle-sections are clockwise, to effect the reverse rotation of the turbine the ring 15 and valves are moved anticlockwise from their normal or "stop" position and reversing nozzle-section groups *efg* are successively uncovered by the valves 45, carried by the inner flange-sections 43, thereby directing the 20 fluid to and through the inner nozzle-sections, blades, and chambers. This wide range of valve adjustment is accomplished by the simple act of moving the ring 40 and valves, which movements are accomplished, preferably, by a pinion 49 and a segmental rack 50 25 on one of the flange-sections 42. The pinions, which in number correspond to the number of moving parts, are housed in recesses 51 in the casing and, preferably at one side, as illustrated in Fig. 3. The showing in Fig. 2 of the 30 valve-adjusting means at the top is for the sake of clearness. The pinions are commonly fixed on a shaft 52, which extends beyond the casting-head and carries a wheel 53, by which it is 35 turned. A pointer 54, movable with the wheel, and a fixed dial 55, suitably marked, determine the direction and extent of movement of the valves.

By reference to Fig. 2 it will be noted that 40 a material clearance is provided between the surfaces of a disk and the walls of adjoining stationary chambers. Owing to the uniform pressure of the body of fluid between the outlet of one nozzle-section and the inlet of the 45 adjacent nozzle-section, there is no tendency to leakage at the disks, and sufficient clearances may be provided to allow of a considerable end thrust of the shaft and yet produce no friction between the surfaces. 50 Between the inner wall 56 of a stationary chamber and the rim 20 of a wheel 19 there is, however, a tendency to leakage, which is avoided by providing in the wall-surface or rim-surface, or in both, recesses 57, forming a 55 fluid-packed joint and creating obstructions to the direct passage of fluid between the wheel-rim and wall of the chamber.

I claim as my invention—

1. In an elastic-fluid turbine, a moving 60 part having surfaces, and a plurality of fluid-nozzles alternately active to create and to direct with equal efficiency fluid at different velocities against said surfaces.

2. In an elastic-fluid variable-speed tur-

bine, a moving part having impact-surfaces, 65 and a plurality of fluid-nozzle sections alternately active to create and to direct with equal efficiency fluid at different velocities against said impact-surfaces.

3. In an elastic-fluid turbine, a moving 70 part having impact-surfaces, and a plurality of fluid-nozzles alternately active to create and to direct fluid at different velocities against said surfaces to move said part at different speeds which are each approximately 75 one-half that of the velocity of the fluid.

4. In an elastic-fluid turbine, a heating-jacket communicating with the fluid-chest and surrounding the portion of the casing in which the fluid retains the major portion of 80 its kinetic energy, and means for retarding the passage of fluid through said jacket.

5. In an elastic-fluid turbine, a heating-jacket through which the fluid passes to the chest, said jacket surrounding the portion of 85 the casing in which the fluid retains the major portion of its kinetic energy, and means in said jacket for retarding the passage of the fluid therethrough.

6. In an elastic-fluid turbine, a heating-jacket surrounding the casing, and means for retarding the passage of the fluid therethrough.

7. In an elastic-fluid turbine, a heating-jacket in communication with the fluid inlet 95 and chest, and means in the jacket providing a spiral path for the fluid.

8. In an elastic-fluid turbine, a moving part consisting of a disk and a plurality of radially-interlocking impact blades or buckets 100 removably fastened to said disk.

9. In an elastic-fluid turbine, a moving part consisting of a disk and a plurality of separately-formed interchangeable impact blades or buckets having means effecting 105 their radial locking with each other and with the disk.

10. In an elastic-fluid turbine, a moving part consisting of a slotted disk and a plurality of separately-formed impact blades or 110 buckets having interlocking means and arms drive-fitted in said slots.

11. In an elastic-fluid turbine, a moving part consisting of a disk formed with radially-disposed slots, and a plurality of radially-interlocking impact blades or buckets having 115 shoulder arms drive-fitted in said slots.

12. In an elastic-fluid turbine, the combination of a rotatable disk having a plurality of radially-disposed slots each having opposite lateral recesses located short of the slot-base, and a plurality of separately-formed impact blades or buckets each having a securing-arm formed with opposite shoulders located short of the end thereof, said arms 120 fitting said slots.

13. In an elastic-fluid turbine, a rotatable disk having a plurality of radially-disposed

- slots the walls of which are intermediately and radially recessed, and a plurality of impact blades or buckets having securing-arms conforming to and fitting said recessed slots.
- 5 14. In an elastic-fluid turbine, a rotatable disk having radially-disposed slots, and a plurality of separately-formed impact blades or buckets having tongues and grooves whereby they are interlocked with each other and 10 having shouldered arms interlocking with said slots.
15. In an elastic-fluid turbine, a rotatable disk having radially-disposed slots, and a plurality of radial separately-formed interlocking impact blades or buckets having shouldered arms engaging said slots, said blades or buckets being drive-fitted to each other and to the disk.
- 20 16. In an elastic-fluid turbine, a section of an adiabatic nozzle, a stationary fluid-chamber having in one wall reaction-surfaces and in the other wall a second nozzle-section and arranged to maintain a uniform pressure between the outlet from the first-named nozzle-section and the inlet to the second nozzle-section, and a moving part carrying impact-surfaces and rotatable between the first-named nozzle and adjacent chamber-wall.
- 25 17. In an elastic-fluid reversible turbine, a stationary chamber having in one wall inner and outer series of passages and in the other wall inner and outer series of nozzles, and a rotatable ring filling the chamber horizontally and dividing it into inner and outer fluid-passages.
- 30 18. In an elastic-fluid reversible turbine, a stationary fluid-chamber divided by a rotatable partition.
- 35 19. In an elastic-fluid reversible turbine, a stationary fluid-chamber having in one wall inner and outer sets of reaction-passages and in the opposite wall inner and outer sets of nozzles, a rotatable partition dividing the chamber, and nozzle-controlling valves carried by the partition.
- 40 20. In an elastic-fluid reversible turbine, a stationary fluid-chamber having in one wall inner and outer sets of impact-surfaces and in the opposite wall inner and outer sets of nozzles, a rotatable partition dividing the chamber and carrying flange-sections, and nozzle-controlling valves carried by said flange-sections.
- 45 21. In an elastic-fluid reversible turbine, a stationary fluid-chamber having in one wall inner and outer sets of impact-surfaces and in the opposite wall inner and outer sets of nozzles, a rotatable partition dividing the chamber and carrying flange-sections, and nozzle-controlling valves yieldingly carried by said flange-sections.
- 50 22. In an elastic-fluid reversible turbine, a stationary fluid-chamber having in one wall inner and outer sets of impact-surfaces and in the opposite wall inner and outer sets of nozzles, a rotatable partition dividing the chamber and carrying flange-sections, and nozzle-controlling valves carried by said flange-sections.
- 55 23. In an elastic-fluid reversible turbine, a stationary fluid-chamber, and a roller-supported rotatable partition dividing the chamber horizontally.
- 60 24. In an elastic-fluid turbine, a fluid-chamber having fluid-nozzles adapted to create different degrees of energy, a ring in the chamber supported to be rotatable, segmental valves on the ring for successively controlling the valves, and means for rotating the ring and valves.
- 65 25. In an elastic-fluid turbine, a fluid-chamber having fluid-nozzles adapted to create different degrees of energy, a ring supported to be rotatable and carrying segmental flange-sections, segmental valves carried by the flange-sections and arranged in the movement of the ring to successively control said nozzles.
- 70 26. In an elastic-fluid turbine, a stationary part, nozzles in said part, a ring supported to be rotatable, segmental valves on said ring and rack and pinion means for moving the ring and valves to successively control said nozzles.
- 75 27. In an elastic-fluid turbine, a stationary part, nozzles in said part, a ring supported to be rotatable, segmental valves on said ring, rack-and-pinion means for moving the ring and valves to successively control said nozzles, a shaft for the pinion, a wheel on the shaft, and a pointer and dial for determining the movements of the valves.
- 80 28. In an elastic-fluid reversible turbine, a stationary part, a concentric set of nozzles adapted to create different degrees of energy, a second concentric set of nozzles adapted to create different degrees of energy and to rotate a movable part in a direction opposite to that of the first-named set, a ring rotatable between the sets, inner and outer valves carried by the ring, rack-and-pinion means for moving the ring and valves in either direction to successively control one or the other set of nozzles.
- 85 29. In an elastic-fluid turbine, a chamber through which the fluid passes, disks carrying impact-surfaces and rotatable at the sides of the chamber, a spacing-wheel separating the disk and extending at its rim to the inner wall of the chamber, and fluid-recesses forming a fluid-packed joint between said wall and rim.
- 90 30. In an elastic-fluid turbine, a plurality of moving parts, spacing elements for said parts, fluid-passages between said parts and means for preventing fluid leakage between the elements and passage-walls.
- 95 31. In an elastic-fluid turbine, a plurality

of moving disks, spacing-wheels separating said disks, annular fluid-passages between the disks and beyond the spacing-wheels, and means providing fluid-packing between the wheel-rims and passage-walls.

32. In an elastic-fluid turbine, a plurality of fluid-chambers through which the fluid passes laterally, a plurality of disks each moving with clearance between the side walls of two chambers, spacing-wheels separating

said disks and means providing fluid-packing between the wheel-rims and inner chamber-walls.

In testimony whereof I affix my signature in presence of two witnesses.

EDWIN F. TAYLOR.
